UNITED STATES PATENT OFFICE

147,842

DESIGN FOR A ROLL TURNTABLE TOP

George Draper, International Falls, Minn., and
Bruce F. Warner, Fort Frances, Ontario, Canada, assignors to Minnesota and Ontario Paper
Company, Minneapolis, Minn.

Application May 3, 1946, Serial No. 129,236

Term of patent 14 years

(Cl. D33—14)

To all whom it may concern:

Be it known that we, George Draper and Bruce F. Warner, citizens of the United States and Dominion of Canada, respectively, residing at International Falls, in the county of Koochiching and State of Minnesota, and Fort Frances, Province of Ontario, Dominion of Canada, respectively, have invented a new, original, and ornamental Design for a Roll Turntable Top, of which the following is a specification, reference being had to the accompanying drawing, forming a part thereof.

Figure 1 is a top plan view of the roll turntable top showing our new design;

Figure 2 is a bottom plan view of the same; and

Figure 3 is a side view of the same.

We claim:

The ornamental design for a roll turntable top, as shown.

GEORGE DRAPER.
BRUCE F. WARNER.
